(57) **CLAIM**

The ornamental design for an animal feeding nipple, as shown and described.

DESCRIPTION

FIG. 1 is a right perspective view of an animal feeding nipple showing our new design;

FIG. 2 is a top plan view thereof;

FIG. 3 is a front view thereof;

FIG. 4 is a back view thereof;

FIG. 5 is a bottom view thereof;

FIG. 6 is a right side view thereof; and,

FIG. 7 is a left side view thereof.
